BY M. M. M. ATTORNEYS

UNITED STATES PATENT OFFICE.

BENJAMIN J. LAVIGN, OF NEW YORK, N. Y.

GARMENT.

1,249,131.

Specification of Letters Patent. Patented Dec. 4, 1917.

Application filed December 23, 1915. Serial No. 68,348.

To all whom it may concern:

Be it known that I, BENJAMIN J. LAVIGN, a citizen of the United States, and a resident of New York, in the borough of Bronx, county of Bronx, and State of New York, have invented certain new and useful Improvements in Garments, of which the following is a specification.

My invention relates to garments for girls and the main object thereof is to provide a pair of bloomers, such as are worn in gymnasiums, which is instantly convertible into a skirt of conventional appearance.

In gymnasiums girls are required to wear bloomers and it is now necessary for a girl to change from a street skirt to bloomers and back again before and after exercises or drills, and it was in order to avoid this necessity that my garment was designed, as well as the present necessity for a girl to carry her bloomers to and from the gymnasium where no locker facilities are provided, as in public schools.

My invention is fully described in the following specification, of which the accompanying drawings form a part, in which like characters refer to like parts in each of the views, and in which:

Figure 1 is a front view of a garment constructed in accordance with my invention, with a portion turned upwardly from normal skirt position;

Fig. 2 is an enlarged section taken on the line 2—2 of Fig. 1 but with the parts in normal skirt position;

Fig. 3 is a fragmentary view of one leg of the garment and showing a preferred draw-string arrangement, said leg not being changed from normal skirt position;

Fig. 4 is a section taken on the line 4—4 of Fig. 3 and showing a step in the converting from normal skirt to bloomer conditions;

Fig. 5 is an enlarged fragment of Fig. 2 but with the parts in a released or detached condition, ready for converting into either normal skirt or bloomer conditions; and

Fig. 6 is a reduced front view of the garment when used as bloomers.

My invention consists primarily in a pair of bloomers 7 having leg portions 8 and 9, a belt or waist-band 10, and suspenders 11 in

detachable connection with the bloomers in the form shown, but which may be in permanent connection or may not be used at all as this forms no part of the invention.

The leg portion 8 is provided with a flap 8^a extending from the crotch of the bloomers to the knee-band and provided with spaced buttons 8^b, and the leg portion 9 is similarly provided with a complementary flap 9^a having button-holes 9^b, for the reception of the buttons 8^b, but these may be replaced by fasteners of any desired form, such as glove fasteners, hooks and eyes, etc.

The flaps 8^a and 9^a are shown only at the front of the garment, but they may be at the rear if desired or at both front and rear, it being the result of my experience that their location at the front is most convenient for the wearer.

Each leg portion is provided with a band formed by a hem to provide a pocket 12 for a drawstring or ribbon 13 of sufficient length to allow full expansion of the leg band, the bottoms of the legs being formed of more material circumferentially than with conventional garments of the bloomer type.

These leg bands may be made in any desired manner but I have shown a preferred form which is especially well adapted to the dual use of the garment, the ribbon 13 being passed through slots 14 and 15 in the inner side of the leg-band to enable the wearer of the garment to readily grasp the ribbon 13, and I also provide a buckle 16 on the ribbon 13 which is capable of receiving a doubled loop of the said ribbon.

On the way to and from the gymnasium the flaps 8^a and 9^a are secured together and the leg bands extended to their limits, and the garment presents a conventional skirt appearance, particularly if the garment is vertically plaited as shown, but I do not confine myself to the particular style of the garment when used as a skirt.

When the wearer reaches the gymnasium all that is necessary for her to do is to disconnect the flaps 8^a and 9^a and tighten the drawstrings around her legs, the flaps 8^a and 9^a disappearing from view in the bunching of the material of each leg portion in tightening the drawstrings.

With the draw-ribbons 13 shown the exposed portion thereof between the slots 14 and 15 is grasped and a desired amount of the ribbon withdrawn in a loop, including 5 the buckle 16, and this loop is passed into the buckle in the usual manner to attain the desired tension around the leg, no string ends being possible and the spare ribbon being within the respective leg portion.

- 10 As will be seen from the foregoing, my garment may be instantly converted into either conventional skirt appearance or into bloomers, and, while I have shown a convenient means for accomplishing this result, I do not limit myself to these particular means but may depart therefrom provided that the changes come within the 15 scope of the appended claim.

Having fully described my invention,

what I claim as new, and desire to secure by Letters Patent, is:—

A pair of bloomers the bottoms of the legs of which are extensible to a relatively great degree, endless draw-ribbons in the bottom of each leg, a buckle for each draw-ribbon adapted to lock therein a fold of the ribbon caused by the drawing of the bottom of the leg, and means for detachably joining said legs when extended to convert the bloomers into a skirt of normal appearance.

In testimony whereof I have signed my name to this specification in the presence of two subscribing witnesses.

BENJAMIN J. LAVIGN.
